CLAIM

The ornamental design for a grill and headlight unit assembly for an agricultural tractor, as shown and described.

DESCRIPTION

FIG. 1 is a front side elevational view of a grill and headlight unit assembly for an agricultural tractor showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a right front side perspective view thereof; and,
FIG. 7 is a pictorial view of an agricultural tractor showing our new design.

A rear elevational view is omitted since our claimed design is hidden in the rear elevational view.

All broken lines form no part of the claimed design.

The article of FIGS. 1-7 of the present design application is a grill and headlight unit assembly for an agricultural tractor. The front grill is disposed at a lower portion of the front of the hood. On the right and left sides of the front grill, two headlights are disposed. At the center of the front grill, a ventilator is disposed. The ventilator has a symmetrical, polygonal shape and has a network structure with a large number of ventilation holes in the network. On the outer side of the ventilator, a triangular ventilator is disposed. On the outer side of the hood, a rhombic ventilator is disposed.
